(57) **CLAIM**

The ornamental design for a personal watercraft hull, as shown and described.

DESCRIPTION

FIG. 1 is a perspective view taken from a bottom, front, left side of a personal watercraft hull according to our design; FIG. 2 is a front elevation view thereof; FIG. 3 is a rear elevation view thereof; FIG. 4 is a right side elevation view thereof; FIG. 5 is a left side elevation view thereof; and, FIG. 6 is a bottom plan view thereof. Throughout the Figures, where shown, the dashed lines and adjacent unshaded surfaces depict portions of the personal watercraft hull that form no part of the claimed design.
